(57) **CLAIM**

The ornamental design for a storage device, as shown and described.

DESCRIPTION

FIG. 1 is a perspective view of the storage device showing our new design;

FIG. 2 is a front elevational view thereof;

FIG. 3 is a rear elevational view thereof;

FIG. 4 and FIG. 5 are side elevational views thereof;

FIG. 6 is a top plan view thereof;

FIG. 7 is a bottom plan view thereof; and,

FIG. 8 is a perspective view thereof in the open position.

The broken lines in FIGS. 1-8 are for illustrative purposes only and form no part of the claimed design.

1 Claim, 6 Drawing Sheets
